SAFETY RAZOR

George Taylor, Penwortham, Preston, England

Application July 10, 1935, Serial No. 30,613
In Great Britain April 25, 1935

7 Claims. (Cl. 30—68)

This invention relates to safety razors and more specifically to a safety razor having an independent guard plate and means for varying its position with regard to the cutting edges of the blade.

The object of the invention is to provide a simple and practical form of device for varying the space between the edge of the blade and the guard so that either a moderate or a keener shave may be obtained depending upon the necessities of the case and depending also upon the particular idiosyncrasies of the person being shaved.

Another object of the invention is to provide a form of clamping device which may be simply sprung into clamping position with the blade in place by the pressure of a finger, and since in a device with a spring clamp the position of the edges of the blade due to flexing is a fixed one, it is found necessary to have some adjustment possible of the guard in relation to the edge of the blade, which it is the aim of this device to provide.

Other objects of the invention will appear in the following description of the accompanying drawing illustrating preferred embodiments of the invention in which:—

Figure 1 is a sectional elevation showing the razor in operative position but with the end adjusted at maximum opening;

Figure 2 is a sectional view on the line A—A of Figure 1;

Figures 3 to 8 show the several parts of Figure 1 separated, namely:

Figure 3 shows a backing plate and stem;

Figure 4 a spring;

Figure 5 an independent guard plate;

Figure 6 the adjusting nut;

Figure 7 the handle and carrier, and

Figure 8 the spring catch;

Figure 9 shows a carrier with pins for guiding same;

Figure 10 shows a spring adapted to fit the guide pins;

Figure 11 is another form of the independent guard plate;

Figure 12 is an underside view of same bearing a scale by which the adjustment of the guard is regulated.

In order to show the details more clearly Figures 1 to 8 are drawn to an enlarged scale and it should be understood that Figures 9 to 12 are employed with a similar handle and carrier to that shown in Figure 1, the only variation being in the means for guiding the guard plate thereon.

Referring first to Figures 1 to 8, 1 is a handle connected with an auxiliary carrier 2, the handle

being provided with a hole 3 into which is pressed the stem 4 on the backing plate 5 provided, as shown, with guide pins 6 entering holes in the carrier 2. The stem 4 is also provided with a groove 7 on its inner end and a tapered extremity 8.

Arranged transversely across the handle is the clasp 10 provided with a hole 11 and having three prongs 12, 13, 14 of which the central one is fitted with a finger disc 15 and the spring 16, the clasp 10 being arranged to slide within the slot 17 in the handle so that the edges of the slot are caught by the spring 16.

By inserting the blade 20 between the backing plate 5 and the carrier 2 and pressing down the stem 4 the groove 7 will be caught by the end of the clasp 10 controlled by the spring 16 and will be instantaneously secured to the carrier with the blade flexed.

Provided on the handle 1 is an enlargement 21 carrying a screw thread, and arranged to engage therewith is the adjusting nut 22.

23 is an independent guard plate provided with the guide pin holes 24 and a central hole 25 through which the handle is passed before the mounting of the nut 22. The guard plate 23 is also provided at each end with recesses 26 into which the ends 27 of the carrier 2 fit, the leaf spring 28 also having end lugs which fit within the recesses 26, while its central portion is cut away at 29 to admit both the handle and the guide pins 6.

It will be seen that the nut 22 is made with a pointer 30 which works in conjunction with a scale such as 31, as shown in Figure 12 where the nut is removed but the pointer 30 is shown diagrammatically to indicate the device; it will be understood that a scale such as 31 is marked also on the underneath side of the guard plate 23 of Figure 5.

The blade having been placed on the backing plate 5 and the stem groove pushed home until caught by the spring clasp 10, it is firmly secured to the carrier 2 by the action of the spring 16, being then permanently fixed as regards its edges 9, 45 9; before the clasp 10 is mounted in the slot 17 the spring 28 and the guard plate 23 are slid into position with the end of the spring 28 and the end 27 of the carrier occupying the recesses 26 of the plate 23. Thereafter the nut 22 can be 50 screwed up on the thread 21 without causing the rotation of the plate 23 about the handle.

On reference to Figure 2 it will be seen that screwing up of the nut 22 pushes up the plate 23 so that its guard edges approach nearer to the 55

blade edges 9, 9, by which means the gap 33 is reduced. The reduction of this gap results in a smooth shave which is not severe on the skin and would be likely to be used by people with a delicate skin.

When a rough shave is required the nut 22 is adjusted in the opposite direction and a keener shave is obtainable; the various settings of the razor gap being adjusted according to the scale 31 and the turning of the nut so that its pointer 30 comes to a particular position on the scale which is found by experience to be the best for the particular individual using the razor.

As will be seen by the markings "Keen" and "Medium" and the accompanying arrows, adjustment takes place and the scale is marked in accordance with a clock (for example) so that an operator will find it easier to remember the position in which to set the adjusting screw.

20 For removal of a blade it is merely necessary to press on the finger disc 15 upon which the spring 16 is mounted, when the hole 11 centralizes itself in relation to the end 8 and the backing plate 5 comes loose due to the action of the blade 25 20 unflexing.

In the device shown in Figures 9 to 12, four pins 34 are used to guide the guard plate 35, corresponding holes 36 being made therein to suit the position of the pins 34, and in this case the 30 end 37 of the guard plate need not be recessed but may correspond to the underside curves of the backing plate 5 as shown in Figure 2.

The normal guide pins 6 of the backing plate will occupy the holes 38, 39 as before.

35 From the preceding description it will be seen that a simple pressure with the finger on the disc 15 immediately releases the blade and a similar pressure on the backing plate returns it to place. Consequently, replacement or removal for 40 cleaning is attained very quickly and by means of a device that is not likely to get out of order, accompanied by means for varying the gap between the blade and the guard, which is highly important in a razor of this character.

45 What I claim is:—

1. The combination with a safety razor having a flexible cutting blade provided with one or more apertures, of a handle, an external thread on the said handle, an auxiliary blade carrier 50 integral with the handle, guide members thereon, a guard plate having apertures for the said guide members, a spring interposed between the said carrier and the said guard plate, and a nut cooperating with the thread on the handle to adjust the guard plate relatively to the blade carrier.

55 2. A safety razor comprising a cutting blade,

an externally threaded handle, a backing plate, a carrier plate integral with the handle, means for removably attaching the backing plate to the handle so as rigidly to hold the blade between the said backing plate and the said carrier plate, an independent guided guard plate riding on the handle, a spring pressing the said guard plate away from the carrier plate, and a nut engaging the thread of the handle whereby the guard plate may be raised in opposition to the said spring. 10

3. The combination with a safety razor having a cutting blade, of an externally threaded handle, a backing plate, a carrier plate integral with the handle, a stem on the backing plate entering a hole in the handle and provided with a 15 grooved end, a spring loaded clasp engaging the groove of the said stem, an independent guided guard plate riding on the handle, a spring pressing the said guard plate away from the carrier plate, and a nut engaging the thread of the handle, whereby the guard plate may be raised in opposition to the said spring. 20

4. A safety razor comprising a cutting blade, an externally threaded handle, a backing plate, a carrier plate integral with the handle, means 25 for removably attaching the backing plate to the handle so as rigidly to hold the blade between the said backing plate and the said carrier plate, an independent guided guard plate riding on the handle, a blade spring having a cut-away centre 30 with its ends bearing against the ends of the carrier plate, and a nut engaging the thread of the handle whereby the guard plate may be raised in opposition to the said spring.

5. A carrier plate as claimed in claim 2 having 35 a plurality of guide pins in combination with a guard plate having a plurality of holes with which the said guide pins engage when the parts are assembled in the razor.

6. In a safety razor as claimed in claim 2, 40 and in combination, a guard plate provided with a central hole to allow of the passage of the threaded handle, guide holes thereon for the reception of guide pins on the backing plate, a blade spring with openings for the passage of said 45 guide pins and end recesses on the guard plate for the purpose of guiding the ends of the blade spring with which it is associated.

7. In a safety razor as claimed in claim 2, 50 and in combination, a guard plate provided with a central hole to allow of the passage of the threaded handle and holes for the reception of guide pins on the carrier plate, and end walls thereon adapted to make contact with the underside of the carrier member.

55 GEORGE TAYLOR.
